MACHINE FOR ORNAMENTING LEATHER,
ETC.René Marc Sichère, Long Island City, N. Y., as
signor to Mechanical Ornamentation Corpora-
tion, a corporation of New York

Application December 9, 1937, Serial No. 178,980

11 Claims. (Cl. 91—49)

My invention relates to means for ornamenting leather, cloth, paper, and other such materials generally used in making shoes, belts, bags, and many other articles of merchandise.

5 The object of my invention is to provide a simple machine constructed to apply coloring matter to a surface to form a band or ribbon-like line or lines extending parallel to each other to simulate a ribbon or cord, etc., or overlay strip-
ping.

10 A further object is to provide a machine operative to make a line or lines of stitching on one or both sides of said band or line simultaneously and progressively with the application of the coloring matter.

15 A further object is to provide a process for and a machine to employ the process for simultaneously applying the colored matter to the material in a line or stripe and to indent the material at one or both sides of the stripe to simulate stitching, or to simultaneously stitch a line or lines adjacent to the stripe.

20 A further object is to provide a container for the coloring matter that is permanently sealed at both ends and is provided with means for holding it in removable relation in the machine.

25 The machine may be constructed as a whole if desired but I prefer to make it as an attachment for sewing machines such as used for sewing leather, etc. and utilize the feeding means thereof and the sewing means in carrying out the process.

30 The drawing which forms a part of this specification discloses a preferred form of construction.

35 Fig. 1 is a perspective view of a machine embodying my invention.

Fig. 2 is a front elevational view.

Fig. 3 is a side elevational view, shown partly in section.

40 Fig. 4 indicates a presser-foot which is carried by an integral shank 11 which extends upwardly therefrom and serves as a support for the mechanism.

45 The shank is formed to provide a rectangular shaped opening 12 the side walls of which serve to guide the casing in a vertical direction.

50 The casing is made in two half parts indicated by 13 and 13', the portion 13' having an integral lug 14 which extends into the opening 12 and fits in sliding engagement with the side walls thereof and is held to the shank 11 by the bolt and nut construction 15.

55 The casing portions are held together by screws 16 and 17 respectively, the portion 13' remaining in position when said screws are removed.

The casing portions are formed to provide a slot 18 of circular form between them, indicated by 18, in which a wheel 19 fits in close sliding contact at its sides, with its lower side 19' normally extending thru the slot 18' and resting in alignment with or slightly below the lower side of the casing and in alignment with or slightly below the lower side of the presser bar, when the presser-bar or foot, is used.

10 The wheel is carried by a shaft on which it is 10 rotatable and the shaft is provided with a screw adjacent to the head 20' which screws into a thread (not shown) formed in the casing portion 13' and serves to assist in holding the casing portions together, as will be readily understood.

15 The outer or tread surface of the wheel 19 is roughened or serrulated in any desired form to carry and deposit a color on a surface such as leather, to simulate a ribbon or tape or cord, etc., and to serve as a means whereby the wheel may 20 be rotated by passing the material in contact therewith in the act of applying the coloring matter thereto.

25 The upper end of the casing is formed to provide a cylindrical part 22 which is open at its 25 upper and lower ends and serves to support a removable container 23 which holds the coloring matter.

30 The container is provided with oppositely extending pins which fit into bayonet shaped slots 30 25 formed in the enlarged top portion 26 of the casing as illustrated.

35 This arrangement prevents the displacement of the container when the machine is in operation and also serves to position the lower end thereof 35 adjacent to the wheel 19.

40 To open the container which is made of soft material, a screw 27 formed with a sharp edge on its inner end, is fitted to screw into the casing wall and extend therethru into contact with the lower 40 end of the container at one side thereof and shear a portion to permit the coloring matter to flow to the tread of the wheel forward of its greatest diameter so that the color will flow in the direction in which the wheel is rotating.

45 Formed in each of the inner side portions of the casing is a shallow groove indicated by 28 which extend in curved form from the forward side of the wheel to a container 29 and serve to collect and carry excess liquid which may leak from the 50 tread of the wheel, to said container.

55 Located above the grooves 28 are grooves 30 which lead from the wheel at 31 to the said container and serve the same purpose.

34 indicates a vertically extending shaft which 55

extends thru the upper wall of the casing at their point of juncture and carries a frusto-conical brush which rests in a chamber 35 and is rotated by means (not shown) which may be automatically driven when the device is operating, or may be manually rotated, the object being to keep the serrations free from dry matter or from becoming clogged by the drying of a part of the matter.

32 indicates a piece of material such as soft 10 rubber, which fits in a slot 33 formed in the casing, and which serves to closely confine the coloring matter in the serrations in the wheel.

The presser-foot 10 is provided with two or more apertures 36 spaced apart thru which 15 needles may pass to indent or puncture the leather or material being treated, to simulate stitching which extends along the band or stripe as it is formed, and a band of colored material similar to a typewriter ribbon may be used to 20 color the needle and carry the color into the indents if desired, said ribbon being indicated by 37 in Fig. 3.

The cross-head 38 carrying the needles may be reciprocated in timed relation with the movement 25 of the material being treated, the sewing machine serving the purpose in the usual manner of stitching, and the eyes of the needles serving to carry the color into the perforations.

The container 29 is used as a drip-pan and 30 may be removed at any time by simply sliding it from its position of rest.

39 indicates a spring which normally holds the casing in its lowest position but permits it to rise a limited distance in case the wheel should encounter a hard substance or that the thickness of the material should vary, thus permitting the machine to follow any uneven surface over which the wheel is passing.

The device may be operated by use of the sewing 40 machine to which it is attached, and which serves to feed the material to the tread of the wheel automatically and at the same time to indent the surface of the material with the needles, as will be readily understood.

45 The process of simulating a ribbon by depositing a band or line of coloring matter on a surface such as leather and simultaneously simulating a stitching along the margin of the band, may be carried out by a machine differing in construction 50 from that shown in the drawing forming a part of this application, the present machine simply illustrating the process and means by which it may be commercially used.

55 Minor changes as to form and details of construction may be made within the scope of the invention as disclosed and therefore I do not wish to be limited in this matter as to such changes as may be made within the scope of the claims allowed.

60 Having thus described my invention I claim as new:

1. A machine of the character described comprising a two part casing, a wheel having a tread surface extending below the casing, a conduit 65 for liquid formed in the casing and leading to the upper side of the wheel, a sealed removable container for liquid carried in and located above and leading to said conduit and wheel; means in the casing for puncturing the lower end of said container; the construction being such that the rotation of said wheel will carry said liquid from the upper side to the lower side thereof.

2. A machine of the character described comprising a casing, a serrated wheel carried by the 70 casing and extending below the same, a conduit

for liquid formed in the casing and leading to the upper side of said wheel, a removable container for liquid supported by the casing and discharging into said conduit in communication therewith; soft yielding material located above 5 the wheel in contact with the tread surface thereof; the construction being such that the rotation of said wheel will confine the liquid to said serrations and carry it to the lower side of the wheel.

3. A machine of the character described comprising a casing formed in two parts held together in separable relation and having an annular slot formed therein, a serrulated wheel fitted to rotate in said slot with its lower end 15 extending below said casing, a shaft for supporting said wheel, a conduit for liquid formed in said casing in open communication with the upper side of said wheel, a separate detachable sealed container for liquid carried in the casing, 20 the lower end of which is located adjacent to the upper side of said wheel and means carried by the casing for puncturing the lower end of the container.

4. A machine of the character described comprising a casing formed in two parts held together in separable relation and formed to provide an annular slot between them, a serrulated wheel fitted in said slot with its lower end extending below the casing, a shaft supporting 30 said wheel and serving to hold the two casing portions together, a conduit for liquid formed in the casing above the wheel and leading to the serrulations therein, a sealed container for coloring matter located entirely above the wheel and 35 arranged to discharge its contents into said conduit and means carried in a wall of the casing for puncturing the lower end of the container.

5. A machine of the character described comprising a casing and formed to provide an annular slot, a serrulated wheel fitted to rotate closely in said slot with its lower side extending below said casing, a shaft for supporting said wheel, a conduit for liquid formed in said casing in communication with the upper side of said 45 wheel, a separate detachable container for liquid the lower end of which is sealed and located adjacent and entirely above the upper side of the wheel, means carried by the casing adapted to puncture the lower end of the container and 50 means for confining a liquid flowing from said container closely in the serrulations of the wheel.

6. A machine for use as an attachment for a sewing machine having a presser-foot and feed mechanism, etc., said attachment comprising a 55 presser-foot formed with an opening in the foot portion thru which the lower side of a wheel may extend, and having a shank portion extending upwardly therefrom formed to provide an opening therein, a casing having a lug portion extending into said opening, means for holding said lug in adjustable relation to permit the casing to move vertically relative to said shank portion.

7. The construction defined in claim 6, together 65 with, a spring located between the casing and shank to effect a resilient yielding action between the casing and shank when pressure is applied to the under side of a wheel carried by the casing.

8. A machine of the character described comprising a presser-foot formed with an opening in the foot portion thru which a wheel may extend, and having a shank portion extending upwardly therefrom and formed to provide an open- 70 75

ing therethru, a casing having a lug portion which extends into said opening, means for holding said casing to said shank in adjustable relation therewith, a wheel having a roughened tread surface carried by the casing and extending below the same and into the opening in the foot portion, a conduit for liquid leading to the upper side of said wheel, and a source of liquid supply in open communication with the tread of said

5 wheel.

9. The construction defined in claim 1, together with; said casing having a chamber formed therein into which said wheel projects, a vertically extending shaft supported in the 15 casing and extending into said chamber, and a brush carried by said shaft and rotatable in contact with the tread of the wheel to clean the same.

10. The construction defined in claim 1, to-

gether with; said casing having a cylindrical formation at its upper end adapted to hold a container, and a container resting in said cylinder with its lower end adjacent the bottom thereof.

11. A machine of the character described comprising a casing, a wheel having a tread surface extending below the casing, a conduit for liquid formed in the casing and leading to the upper side of the wheel, a removable container for liquid carried by and located above and leading to said conduit and wheel; the construction being such that the rotation of said wheel will carry said liquid from the upper side to the lower side thereof, and a rotatable brush carried in the 10 casing in contact with the serrations in the 15 wheel for cleaning the serrations.
